UNITED STATES PATENT OFFICE.

MORTIMER V. TESSIER, OF NYACK, NEW YORK, ASSIGNOR TO AMERICAN TOBACCO COMPANY, OF NEW YORK, N. Y., A CORPORATION OF NEW JERSEY.

DESIGN FOR A CAN OR CONTAINER.

43,486.

Specification for Design.

Patented Jan. 21, 1913.

Application filed October 28, 1912. Serial No. 728,293. Term of patent 14 years.

To all whom it may concern:

Be it known that I, MORTIMER V. TESSIER, a citizen of the United States, residing at Nyack, county of Rockland, State of New York, have invented a new, original, and ornamental Design for Cans or Containers, of which the following is a specification, reference being had to the accompanying drawing, forming part thereof.

Figure 1 is a front elevation of a can or

container having the design applied thereto. Fig. 2 is a top plan view of the same.

I claim:

The ornamental design for a can or container, as shown.

MORTIMER V. TESSIER.
